US00D566216S

(12) **United States Design Patent** (10) **Patent No.:** **US D566,216 S**
Mayer et al. (45) **Date of Patent:** **** Apr. 8, 2008**

(54) **ICE SKATE BLADE GUARD ROLLER APPARATUS**

3,135,526 A 6/1964 Johns
3,281,971 A 11/1966 Weitzner
3,292,940 A 12/1966 Weitzner
3,338,588 A 8/1967 Couture
3,583,720 A 6/1971 Fowlkes

(75) Inventors: **Dave Mayer**, St. Charles, MI (US);
Victor Posa, Grand Blanc, MI (US);
Paul M. Steinhauer, Jr., Davison, MI
(US)

(Continued)

(73) Assignee: **Rollergard, L.L.C.**, St. Charles, MI
(US)

FOREIGN PATENT DOCUMENTS

CH 604785 9/1978

(**) Term: **14 Years**

Primary Examiner—Holly H. Baynham

(21) Appl. No.: **29/278,153**

Assistant Examiner—Cynthia M. Chin

(22) Filed: **Mar. 21, 2007**

(74) *Attorney, Agent, or Firm*—Robert L. Stearns;
Dickinson Wright PLLC

(51) **LOC (8) Cl.** **21-02**

(57) **CLAIM**

(52) **U.S. Cl.** **D21/771; D21/772**

The ornamental design for an ice skate blade guard roller apparatus, as shown and described.

(58) **Field of Classification Search** D21/760-764,
D21/771, 772; 280/7.1-7.17, 841, 11.115,
280/11.12, 11.19, 11.221, 11.231, 809, 811

See application file for complete search history.

FIG. 1 is a first perspective view of the ice skate blade guard roller apparatus;

FIG. 2 is a second perspective view of the ice skate blade guard roller apparatus;

FIG. 3 is a top view of the ice skate blade guard roller apparatus;

FIG. 4 is a bottom view of the ice skate blade guard roller apparatus;

FIG. 5 is a left-hand view of the ice skate blade guard roller apparatus;

FIG. 6 is a right-hand view of the ice skate blade guard roller apparatus;

FIG. 7 is a front view of the ice skate blade guard roller apparatus; and,

FIG. 8 is a back view of the ice skate blade guard roller apparatus. The broken lines are for illustrative purposes only and form no part of the claimed design.
